UNITED STATES PATENT OFFICE

2,621,510

KEY CONTROLLED CYLINDER LOCK

Richard Ramhøj, Copenhagen, Denmark

Application July 30, 1947, Serial No. 764,655
In Denmark June 20, 1946Section 1, Public Law 690, August 8, 1946
Patent expires June 20, 1966

3 Claims. (Cl. 70—363)

1

The present invention relates to an improved cylinder lock with key.

Cylinder locks are already known which have an exterior cylinder provided with an interior rotatable barrel operable from either end by means of a key, and coacting with a lock-bolt. The interior barrel may be locked to the exterior cylinder by means of a locking ring and locking pins displaceable longitudinally in peripheral grooves in the barrel. A disadvantage of such known cylinder locks is that they can only be employed in connection with the particular lock construction for which they are intended.

The object of the present invention is to provide a cylinder lock of the type mentioned above, which can be applied to any lock construction in which such cylinder locks are employed.

The invention is more explicitly explained in the following specification with reference to the accompanying drawing, in which

Fig. 1 is a longitudinal section through a cylinder lock according to the invention, on line I—I in Fig. 2 with the locking pins in their locking position in relation to the locking ring,

Fig. 2 is a transverse section through the lock shown in Fig. 1, on line II—II in Fig. 1,

Fig. 3 is a similar view to Fig. 1 but with key inserted displacing the locking pins to their unlatching position in relation to the locking ring,

Fig. 4 shows one end of the key in side elevation, and

Fig. 5 is an end elevation of the key shown in Fig. 4,

Fig. 6 shows in end elevation an end plate, and

Fig. 7 shows in side elevation one end of the lock barrel.

The lock cylinder consists of two cylinder parts 12 and 12a of approximately equal length that are relatively spaced and interconnected by means of an arched bridge 8. The one cylinder part 12 has around its inner end a recessed portion 17 to which is applied a flanged locking ring 7 which along its interior edge has a number of arcuate recesses 19. This locking ring is by appropriate means attached to the cylinder part to prevent its rotation in relation thereto.

A lock barrel 11 is rotatably journaled within the two cylinder parts 12 and 12a. This barrel is provided with several, for instance four longitudinal bearings 10 disposed so close to the periphery of the barrel that each boring forms an open space along the barrel surface. At each end the barrel is provided with an end plate 4 provided with four recesses of which the three recesses 22 each engage a projection 13 on the

2

barrel end, the fourth recess 22a being left open for reasons stated later.

Within each bearing 10 is inserted a locking pin 1 which at each end carries a longitudinally extending guide pin 2 for a coil spring 5 interposed between the end of the locking pin 1 and the base of a boring 3 in the aforesaid end plate 4. Thus each pin 1 is resiliently disposed between the end plates 4 attached to the barrel 11. Each locking pin 1 has furthermore two annular grooves 9 and 9a, one on each side of the locking ring 7. The part of each locking pin 1 projecting through the open space along the periphery of the barrel 11 engages one of the arcuate recesses 19 in the locking ring 7, and consequently the barrel is prevented from rotating in the cylinders 12 and 12a. The position of the annular grooves 9 and 9a on the various locking pins 1 in relation to the locking ring 7 may differ.

The cylinder lock is operated by means of a key 20, which is inserted through an aperture 14 in the one or the other end wall of the cylinders 12 or 12a and is provided with a bit 23, which enters the recess 22a mentioned above in the end plate 4. The key has shoulders 21, which are so positioned that they engage the locking pins and displace them to a position in which the annular grooves 9 or 9a of the locking pins 1 register with the locking ring 7 and thus release the barrel in relation to this locking ring. By means of the key the barrel can be fully rotated within the cylinder.

The barrel 11 has connected thereto a radially extending locking bolt 16 so positioned that upon rotation of the barrel the arm moves within the space between the cylinder parts 12 and 12a inside the bridge 8. This locking bolt coacts with a striking plate not shown.

I claim:

1. A cylinder lock comprising in combination stationary tubular holding members arranged oppositely and spaced from each other; a stationary locking ring arranged upon one of the said holding members in the space formed between said stationary tubular holding members so as to leave between itself and the other of said holding members a slot; a stationary connecting member connecting said two stationary tubular holding members so as to be spaced from the edge of said slot; a freely rotatable lock barrel passing through said stationary locking ring and projecting into both said oppositely arranged stationary tubular holding members; at least one locking member arranged within said lock barrel slidably in longitudinal direction of the same and

shaped so as to project beyond the surface of said lock barrel and to be adapted to engage when in locking position said stationary locking ring, preventing turning of said lock barrel; spring means arranged between said stationary tubular holding members and said locking member tending to keep the same in locking position; an opening at the outer end of each of said stationary tubular holding members through which said locking member can be reached by means of a key and moved from locking position into unlocking position in which it does not engage said stationary locking ring; and a lock controlling projection on said freely rotatable lock barrel arranged outwardly projecting through said slot.

2. A cylinder lock comprising in combination two stationary tubular holding members arranged oppositely and spaced from each other so as to form a slot between themselves; locking means arranged on one of said stationary tubular holding members projecting inwardly into the space between the same; a freely rotatable lock barrel arranged within said tubular holding members; a lock controlling projection on said freely rotatable lock barrel arranged outwardly projecting through said slot; connecting means firmly connecting said tubular holding members so as not to interfere with turning of said lock controlling projection when the same is turning together with said freely rotatable lock barrel; at least one locking member arranged within said lock barrel slidably in longitudinal direction of the same and projecting beyond the surface of said lock barrel in such a manner as to be adapted to engage when in locking position said locking means, preventing turning of said lock barrel; and means for moving said locking member in longitudinal direction of said lock barrel so as to move it out of engagement with said locking means, thereby enabling turning of said lock barrel and said lock controlling projection thereof.

3. A cylinder lock comprising in combination stationary tubular holding members arranged op-

ositely and spaced from each other so as to form a slot between themselves; locking means arranged on one of said stationary tubular holding members projecting inwardly into the space within the same; a freely rotatable lock barrel arranged within said tubular holding members and provided with at least one longitudinal groove; a lock controlling projection on said freely rotatable lock barrel arranged outwardly projecting through said slot; connecting means firmly connecting said tubular holding members so as not to interfere with turning of said lock controlling projection when the same is turning together with said freely rotatable lock barrel; a locking member arranged within said longitudinal groove freely slidably within the same in longitudinal direction of said lock barrel between locking position engaging said locking means and preventing turning of said lock barrel and unlocking position out of engagement with said locking means and permitting turning of said lock barrel; two spring means arranged within said groove, one on each side of said locking member tending to hold the same in locking position engaging said locking means; and an opening at the outer end of each of said oppositely arranged stationary tubular holding members enabling introduction of a key into said groove and movement of said locking member from the outer side of either of said holding members from locking into unlocking position in which latter position said lock barrel is turnable by said key.
